DUMPING SCRAPER

Frank Roshak, Tigard, Oreg.

Application October 11, 1937, Serial No. 168,435

4 Claims. (Cl. 37—140)

This invention relates to scrapers and is especially adapted to be used in connection with dump scrapers.

The primary object of the invention is to provide a locking means for holding the scraper blade against rotation.

Another object of the invention is to provide locking means so designed that it can not be sprung out of place. In my new and improved 10 lock the strain against the lock by the turning action of the scraper is transferred directly to the frame of the machine and the locking bar resists any bending action directed thereagainst.

A further object of my invention is to provide 15 a locking means that can be easily controlled from a distant point such as the tractor that may be pulling the scraper.

Another object of my invention is to provide 20 a locking means that will allow the scraper blade to revolve when the tractor and blade are reversed.

These and other incidental objects will be apparent in the drawing, specification and claims to follow.

25 Referring to the drawing:

Figure 1 is a side elevation of a well known type of dumping scraper having my improved lock mounted thereon.

Figure 2 is a plan view of Figure 1.

30 Figure 3 is a fragmentary plan view of the tongue of the scraper, more clearly illustrating part of the locking mechanism.

Figure 4 is a fragmentary detail sectional view, taken on line 4—4 of Figure 2, looking in the 35 direction indicated.

In the drawing:

1 is a conventional revolving scraper hopper, having a cutting blade 2 and cylindrical end 3. Scraper 1 is journaled to side bar members 4 of frame 5 by pins 6. Frame 5 is secured to a tongue 7 at its forward end and to the rear of the tongue by cross members 5A. Locking bars 8 are pivotally mounted to the frame at 9 at their one end, and are pivotally connected to control rods 10 at their other ends. Control rods 10 are pivotally connected at 11 to bosses 12, which are secured to a sliding rod 13. Rod 13 is slidably mounted in supporting guides 14. A boss 15 is also formed as part of the bar 13 and it is connected to lever 16 by a rod 17. Lever 16 is pivotally mounted at 18 to an upwardly extending bracket 19, said bracket, in turn being mounted to tongue 7.

Referring to Figures 1 and 2, the end 7A of the tongue is assumed to be fastened to the draw-

bar of the tractor, not here shown. The pull cord 20 from lever 16 extends to the tractor and in the event it is desired to unlock the scraper permitting the blade 2 to revolve the cord 20 is pulled forward rocking lever 16 upon its pivot 5 support 18 pulling the rod 17 and slide rod 13 to the right, this moves outwardly the rods or connecting links 10 unlocking the bars 8 from the stop 21, permitting the blade 1 to revolve. A spring 22 is also connected to the boss 15 and 10 to the frame at 23 and is for the purpose of returning the locking mechanism to the position shown in Figures 1 and 2.

Referring to Figure 4, a guiding bracket 24 is mounted to the frame 5 by the bolt 25 and is 15 hooked under the frame 5A as shown at 26. The guiding bracket guides the locking bars 8 upon the frame. The stops 21 have a cam surface 21A permitting the scrapers to be revolved backwards without manipulating the lever 16, the cams 20 moving the locking bars outwardly when the scraper is revolved backwardly, or to the right viewing the several figures of the drawing. Normally the forward faces of stops 21 engage the locking bars 8 and prevent forward rotation of 25 the scraper until such bars are moved out of engagement therewith by rocking lever 16 as heretofore explained.

As stated before the locking bars rest firmly on the upper surface of the frame at pivot point 30 9 and at points intermediate their lengths. This solid support forms a rigid stop for the stops 21.

I do not wish to be limited to this particular form of construction as different mechanical variations may be used still coming within the scope 35 of the claims to follow.

I claim:

1. In a scraper, a scraper body, a frame journaled thereto having a tongue, locking bars pivoted to lateral extremities of the frame, a member 40 slidably connected with the tongue, connecting members between the slidably member and locking bars whereby when the slidably member moved rearwardly the locking bars are pivoted outwardly and when the member is moved forwardly the locking bars are pivoted inwardly, means yieldably normally holding the member and locking bars in the latter position, means for moving the slidably member against the action of the yieldable means, and stops mounted to the 45 scraper body engaging locking bars when positioned inwardly and preventing forward rotation of the scraper body.

2. In a scraper, a scraper body, a frame journaled thereto having a tongue, locking bars piv- 55

oted to the frame and pivotally riding on said frame, a guideway in the tongue, a member slid-
able in such guideway, connecting members be-
tween slidable member and locking bars whereby
5 when the slidable member is moved rearwardly
the locking bars are pivoted outward, and when
the member is moved forwardly the locking bars
are pivoted inwardly, and stops mounted to the
scraper body engaging locking bars when in in-
10 ward position and preventing forward rotation of
the scraper body.

3. In a scraper, a scraper body, a frame jour-
naled thereto having a tongue, locking bars pivot-
ed upon the frame, a member slidably supported
15 by the tongue, connecting means between slidable
member and locking bars which when the slidable

member moves rearwardly pivots the locking bars
outwardly and when moved forwardly pivots the
locking bars inwardly, stops mounted to the
scraper body engaging the locking bars when
such bars are in inward position and preventing
the forward rotation of the scraper body, and
cam means on the stops for moving the locking
bars outwardly so that the scraper body can rotate
rearwardly. 5

4. The invention as set forth in claim 3 in-
cluding spring means for holding the slidable
member in normal forward position, and a lever
connected thereto for sliding it to rearward po-
sition. 10
